UNITED STATES PATENT OFFICE.

GURLEY BROSHEARS, OF NEWBURG, INDIANA.

ADJUSTABLE LINE-SUPPORTING POST.

1,350,208.

Specification of Letters Patent. Patented Aug. 17, 1920.

Application filed November 14, 1919. Serial No. 338,108.

To all whom it may concern:

Be it known that I, GURLEY BROSHEARS, a citizen of the United States, residing at Newburg, in the county of Warrick and 5 State of Indiana, have invented new and useful Improvements in Adjustable Line-Supporting Posts, of which the following is a specification.

The object of my present invention is 10 the provision of a vertically adjustable line-supporting post adapted to be used in a store or in the open, and embodying many practically advantageous features.

To the attainment of the foregoing, the 15 invention consists in the improvement as hereinafter described and definitely claimed.

In the accompanying drawings, hereby made a part hereof:

Figure 1 is an elevation showing my novel 20 post as arranged for use between two posts in the open.

Fig. 2 is an elevation of the post taken at right angles to Fig. 1.

Fig. 3 is a view at right angles to Fig. 1, 25 and showing in elevation the side of the post opposite to that shown in Fig. 2.

Fig. 4 is a horizontal section taken in the plane indicated by the line 4-4 of Fig. 1, looking downwardly.

30 Figs. 5 and 6 are detail views illustrative of the coöperation of the vertically adjustable rack bar and the line holder.

Figs. 7 and 8 are detail views illustrative of the construction complementary to the 35 pinion shaft and the operating crank.

Fig. 9 is a view of the base member for use when the post is to be situated in the open.

Fig. 10 is a detail view of the base member 40 for use when the post is to be used in a store.

Similar numerals of reference designate corresponding parts in all of the views of the drawings.

45 When my improvement is to be used in the open, I resort to a base member 1, of the construction best shown in Fig. 9. The said base member includes a hollow body 2 adapted to be sunk in the ground, and a reduced upper portion 3 in which is a transverse aperture 4.

The base member 1^a, Fig. 10, for use in a store, is provided with an upstanding reduced portion 3 in which is a transverse 55 aperture 4, and is also provided with an apertured base flange 5, as clearly shown

in Fig. 10, the said base flange being adapted to rest upon and be affixed to a floor.

My novel post comprises two hollow opposed sections 6 in which are apertures 7 60 for the drainage of any water that may find its way into the interior of the post. The lower end portions of the section 6 are notched at 8, to rest over the upper portion 3 of the particular base member employed, 65 and said sections are fixedly connected to said upper portion 3 through the medium of a transverse bolt 9. The sections 6 are provided at an intermediate point in their height with opposed apertured lugs 11, connected by bolts 12. The sections are also formed as shown to provide vertical slots 13, Figs. 2 and 3, and the upper ends of the sections are reduced, as indicated by 14, and are connected together by a bolt 15, 70 which also serves for the connection of a bail 16 to which a guy wire may be conveniently connected when the same is deemed necessary.

Movable vertically in the post is a rack-bar 17, and journaled in one section of the post is a horizontal shaft 18 on which is fixed a pinion 19 inside of the post; the said pinion 19 being intermeshed with the rack-bar 17. Pivoted to one side of the 85 post is a spring-pressed latch 21, designed to permit upward movement of the rack-bar 17 while preventing casual downward movement thereof.

The upper portion 22 of the rack-bar 17 90 is guided in upright ways 23 in the inner sides of the post sections, and is equipped as best shown in Figs. 5 and 6—*i. e.*, is provided with a lower aperture 24 and an upper aperture 25, both in alinement with the 95 slots 13, and is also provided with a kerf 26 that extends from the lower aperture to the upper aperture, and from the upper aperture to the upper end of the rack. At 27 is the line-holder of my improvement. 100 This line holder is in the form of a pin, with an enlargement 28 at one end, and an eye 29 at its opposite end, and a reduced intermediate portion 30. When the post is to be used in a store, one end of a line is connected to a store wall and the other end of the line is connected to the eye 29. The intermediate portion 30 of the pin is then passed downwardly through the kerf 26, and the pin is then drawn endwise until its 110 enlargement 28 brings up against the rack-bar 17 and its portion adjacent to the en-

largement 28 rests in the upper comparatively large aperture 25 of the rack-bar, when the line holder will manifestly be strongly connected to the rack-bar without 5 liability of accidental disconnection or displacement.

When my novel post is to be used between two posts 40 spaced therefrom, the line is connected at one end to one post 40 and is 10 threaded through the lower aperture 24 in the rack-bar 17, and is then connected to the other post 40, after which the line holder 27 is positioned in the upper aperture 25, with a view to retaining the line in the lower aperture 24.

When the intermediate portion of a line is secured in the lower aperture 24 in the manner described, it is not feasible to turn the crank 50 through a complete circle, and I 15 therefore resort to the construction clearly 20 shown in Figs. 7 and 8. In the said construction, Figs. 7 and 8, the shaft 18 is provided exteriorly of the hollow post with a toothed disk 60 that is fixed to the shaft, and loosely 25 mounted on the extended portion of the shaft and loosely receiving the said disk 60, is a body 61, having a portion 62, of circular form in cross-section, disposed at right angles to the shaft 18. The said portion 62 is slotted at 30 63 for the reception of detents 64 adapted to coöperate with the teeth of the disk 60. At 35 65 the portion 62 is provided with a stop-pin, and mounted on the said portion 62 and adapted to be turned about the same, and also 40 about the detents 64, is a sleeve 66, the exterior of which is preferably knurled as shown. The said sleeve 66 is provided at its outer end with two opposite stops or abutments 67 and 68, and the interior of the 45 sleeve is of elliptical form, in cross-section. Thus when the sleeve is in one position with one of its abutments against the stop-pin 65, the working ends of the detents 64 will be 50 free to move outwardly, and hence permit the crank 50 that is preferably integral with the portion 60, to be oscillated about the shaft 18, and in that manner the rack-bar 17 may be raised in a step by step manner, the latch 21 then serving to prevent downward or retrograde movement of the rack-bar. When, however, the sleeve 66 is turned to place its other abutment against the stop-pin 65, the working ends of the detents 64 will be held to the disk 60 and against

outward movement, and then the crank 50, 55 the toothed disk 60, the body 61, the detent 64 and the sleeve 66 will be adapted to turn as one piece. When the parts are so arranged, it will be manifest that the rack-bar 17 may be raised or lowered by continuous 60 rotary motion of the crank 50, the latch 21 being of course held out of engagement with the ratchet wheel 20 when the rack-bar 17 is to be moved downwardly.

It will be apparent from the foregoing 65 that through the medium of my novel post, a line may be expeditiously and easily raised after clothes have been placed thereon; also, that the line may be adjustably maintained at various heights, and when desired the line may be as readily lowered.

It is within the purview of my invention to construct my improvement of any material or materials compatible with its purpose, and therefore the improvement may be 70 75 constructed of any material or materials in the discretion of the manufacturer.

Having described my invention, what I claim and desire to secure by Letters-Patent, 80 is:

1. Line supporting means comprising a hollow post with openings in opposite walls, a bar adjustably mounted in the post and having in its upper portion and in registration with said openings a lower aperture, an 85 upper comparatively large aperture, a kerf between and connecting said apertures and another kerf extending from the upper aperture to the upper end of the bar, and a line holder having an enlargement at one end and 90 a reduced intermediate portion adapted to pass through the upper kerf in the bar and also having adjacent to the said enlargement a portion adapted to snugly occupy the upper comparatively large aperture in the bar. 95

2. The combination with a bar having in its upper portion a lower aperture, an upper comparatively large aperture, a kerf between and connecting the said apertures and another kerf extending from the upper aperture and open at its outer end; of a line holder having a reduced intermediate portion adapted to pass through the upper kerf in the bar and also having a portion adapted to snugly occupy the upper comparatively 100 105 large aperture in the bar.

In testimony whereof I affix my signature.

GURLEY BROSHEARS.
